UNITED STATES PATENT OFFICE.

RUSSELL HART, OF LOS ANGELES, CALIFORNIA.

PHOTO-ELECTRIC MEANS FOR REPRODUCING SOUND FROM GRAPHICAL RECORDS.

Application filed October 27, 1924. Serial No. 746,236.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to photo-electric means for reproducing sound from graphical sound records. In a general way it may be said that its objects are to improve the quality or fineness of reproduction of sound from such records, above that obtainable by hitherto developed means. In the case of mechanical reproduction of sound from phonographic records a heavy blunt needle is unable to accurately pick out and respond to the very delicate and rapidly occurring undulations corresponding to the higher frequency overtones. The quality of the reproduced sound is changed by the blurring or partial omission of the overtone reproduction. If a light and sharp needle is used the overtones are more fully represented and the quality of the reproduction is improved unless adversely affected in other respects. In an analogous manner it is the principal object of the present invention to fully reproduce sound from graphical records, without blurring or distorting the finest overtones represented.

More specifically, and in addition, my principal objects are; first, to provide sound reproducing means that are responsive to exceedingly small variations in graphical sound records; second, to furnish facilities for clearly differentiating periodicity in reproducing from such a record, so that the influence of the highest overtones will not be lost or distorted; third, to reduce the amount of light that has been required hitherto for photo-electric sound reproduction; and, fourth, to obtain the above results by means of apparatus of great simplicity and relatively low cost.

My invention is particularly adapted for the reproduction of sound from photographic film records, but may be used also for reproducing other graphical sound records. I prefer to use a photographic film record of substantially constant density and vari-

able width, but a film having a record of uniform width and variable density may be used with practically equal facility.

The objects of the invention are attained in the manner illustrated in the accompanying drawing, in which—

Figure 1 is a diagram showing a typical arrangement of my apparatus for reproducing sound from a photographic film record;

Figure 2 is a front elevation of a portion of a photographic film with a sound record thereon; and the "gate" through which it is made to slide and by which it is definitely positioned;

Figure 3 is a longitudinal section of the above gate and film;

Figure 4 is a rear sectional elevation of a preferred type of photo-electric cell I employ with my apparatus; and

Figure 5 is a side elevation of the above cell.

Similar reference numerals refer to similar parts throughout the several views.

As illustrated, the sound record 6 consists of a photo-exposed and developed area of substantially uniform density and very variable width, appearing as a relatively narrow longitudinal band parallel to, and near one edge of, a motion picture film 7. It is usually preferable to have the outer edge 8 of this record rectilinear, and this edge may then be considered to represent the axis of abscissæ of a very irregular curve 6 corresponding to the recorded sound wave. The ordinates of the curve may be considered to represent volume of sound, or loudness, and the distance between peaks, or corresponding points on the curve, correspond to pitch. The overtones and fundamentals of the recorded sound determine the shape of curve 6. In prior applications for United States Patents No. 608,499 filed Dec. 22, 1922 and No. 630,870 filed Apr. 9, 1923, I have shown and described means for producing such a sound record on a uniformly moving photographic film, and the recording process need not be described herein since it has nothing to do with the present invention.

The type of photographic film record described, or a similarly produced type having a record of uniform width and variable density, is made to travel for reproducing purposes at the recording speed through a "gate" 9. This may be accomplished by driving the film sprocket 10 by means of a

motor 11, the film being unwound from reel 12 and re-wound upon reel 13. Figure 1 is diagrammatic rather than pictorial, and does not illustrate the mechanism by which reel 13 is driven to accomplish the re-winding. Such means, however, are well known to those familiar with the motion picture and allied arts.

A source of light 14, preferably but not necessarily in the form of a luminous filament of substantial thickness, parallel to the plane of the film, and at right angles to its direction of motion, is mounted upon an adjustable clamp 15 so that the filament may be accurately positioned opposite an aperture 16 in gate 9. Rays from the light source pass through aperture 16, the sound recorded portion of film 7, a rear aperture 17 in the gate, and thence through a lens system 18 by means of which they are focused upon a photo-electric cell 19. The focusing is carefully and accurately done to form a very sharp image of the sound record upon the plane of the cell. The cell is mounted upon an adjustable clamp 20 so that it may be accurately positioned.

The photo-electric cell I use with this apparatus is shown enlarged in Figs. 4 and 5. In its best form it comprises a thin plate 21 of quartz on which a thin strip 22 of platinum has been deposited. Subsequently a film of silver is deposited upon the platinum and connecting wires 23 are soldered to this. The metallic strip is then transversely divided by a very narrow rectilinear scratch, and the latter is filled with selenium or other suitable photo-electric material bridging across the severed ends of the platinum strip. There is thus produced a very tenuous bridge 24 of photo-electric substance in electrical contact with a conductor at each side. Finally a cup 25 containing anhydrous calcium chloride is sealed to the quartz plate enclosing the selenium filled scratch.

A process for making an exceedingly sensitive and rapid photo-electric cell of the above described type has been fully described in United States Patent No. 1,491,040 issued to me on April 22, 1924 and the process is not claimed herein.

In operation the apparatus is assembled and adjusted so that filament 14, apertures 16 and 17, lenses 18, and selenium bridge 24, are in accurate alignment along the axial line 26. The luminous filament and selenium bridge are also adjusted parallel to each other and to the apertures in the gate. Lenses 18 are then adjusted to accurately focus an image of the sound record upon the plane of the selenium bridge.

With the above adjustments properly made a constantly varying amount of light, corresponding to variations in the sound record, will be transmitted by the film as it passes the gate apertures. This varying

light flux, focused upon the selenium bridge, will proportionately vary the electrical resistance of the latter, and thus make it possible to reproduce the original sound by telephonic means.

There are various well known means for amplifying a small electric current, modulated by the action of a photo-electric cell, to make it available for operating loud-speaking devices. One method of doing this is illustrated diagrammatically in Fig. 1 wherein certain standard electrical devices are conventionally shown. In this diagram a loud-speaking instrument is indicated at 27, an audion at 28, a variable ratio transformer at 29, and a variable resistance at 30. The diagram shows a satisfactory manner for connecting these devices to batteries 31 and 32, with my photo-electric cell 19 in circuit in the system.

I desire to point out that only that portion of the light transmitted through the sound record which actually falls upon the selenium bridge has any effect upon the reproduced sound. This bridge is very tenuous (preferably not over one thousandth of an inch in width) and thus makes it possible to reproduce sound with extreme accuracy and fidelity as to quality. There is practically no blurring of the sound due to overlapping the effects of adjacent portions of the sound record.

The use of quartz upon which to deposit the photo-active material of the cell is desirable on account of the optical qualities of this substance, and also because its coefficient of expansion is very small or negligible.

Having thus fully described my invention I claim:

1. Photo-electric sound reproducing means comprising; a source of light; a movable optical film with a sound record thereon adapted for modulating rays transmitted from said source; a rectilinear photo-electric bridge of relatively great tenuity disposed parallel to the plane of said film transversely to its direction of motion and exposed to the action of said modulated rays; and a lens intermediate said record and said bridge whereby an image of the former may be focused upon the latter.

2. Photo-electric sound reproducing means comprising; a source of light; a movable optical film with a sound record thereon adapted for transmitting modulated rays from said source; a rectilinear photo-electric bridge of relatively great tenuity disposed parallel to the plane of said film transversely to its direction of motion and exposed to the action of said modulated rays; a lens intermediate said record and said bridge whereby an image of the former may be focused upon the latter; and facilities for reproducing the motion of the film when said record was made thereon.

3. Photo-electric sound reproducing means comprising the elements set forth in claim 2 in combination with; means for passing an electric current through said bridge for modulation thereby; and means for utilizing said modulated current for the reproduction of sound.
4. Photo-electric sound reproducing means comprising the elements set forth in claim 10 2 in combination with; means for passing an electric current through said bridge for modulation thereby; and means for amplifying and telephonically utilizing said modulated current for the reproduction of sound.
- 15 5. Photo-electric sound reproducing means comprising; an illuminable rectilinear filament; a uniformly movable optical film having a sound record thereon adapted for variably transmitting rays from said filament; 20 a photo-electric cell having a tenuous filament of photo-electric material disposed parallel to the plane of said film transversely to its direction of motion in the path of said transmitted rays; and a lens intermediate 25 ate said record and said photo-electric filament whereby an image of the former may be focused upon the latter.
6. Photo-electric sound reproducing means comprising; an illuminable rectilinear filament having means for angularly adjusting its position about a transverse axis; a uniformly movable optical film disposed parallel to said filament and having a sound record thereon adapted for variably transmitting rays from said filament; a photo-electric cell having a tenuous filament of photo-electric material disposed parallel to the plane of said film transversely to its direction of motion in the path of said transmitted rays; a lens intermediate 40 said record and said photo-electric filament whereby an image of the former may be focused upon the latter; and a circuit including said photo-electric filament and telephonic sound reproducing means, whereby an electric current may be modulated by co-action of said
- transmitted rays and said photo-electric filament.
7. Photo-electric sound reproducing means comprising; an illuminable rectilinear filament; a uniformly movable optical film disposed parallel to said filament and having a sound record thereon adapted for variably transmitting rays from said filament; a photo-electric cell, having a tenuous filament of photo-electric material disposed in the path of said transmitted rays parallel to the plane of the film, and angularly adjustable about a transverse axis; a lens intermediate 55 said record and said photo-electric filament whereby an image of the former may be focused upon the latter; and a circuit including said photo-electric filament and amplifying telephonic sound reproducing means, whereby an electric current may be modulated by co-action of said transmitted rays and said photo-electric filament. 60
8. Photo-electric sound reproducing means comprising; an illuminable rectilinear filament having means for angularly adjusting its position about a transverse axis; a uniformly movable optical film disposed parallel to said filament and having a sound record thereon adapted for variably transmitting rays from said filament; a photo-electric cell, having a tenuous filament of photo-electric material disposed in the path of said transmitted rays parallel to the plane of said film and angularly adjustable 70 about a transverse axis; a lens intermediate 75 said record and said photo-electric filament whereby an image of the former may be focused upon the latter; a circuit including said photo-electric filament whereby an electric current may be modulated by co-action of said transmitted rays and said photo-electric filament; means for amplifying said modulated current; and telephonic apparatus whereby said amplified current may be made to reproduce sound. 80 85
